COLLAPSIBLE IRONING TABLE

William H. Maynard, Winooski, Vt., assignor to
Porter Screen Company, Winooski, Vt., a cor-
poration of Vermont

Application March 15, 1934, Serial No. 715,593

6 Claims. (Cl. 68—10)

My invention relates to ironing tables or boards and more particularly to a novel and efficient construction and arrangement of collapsible legs and/or supporting elements for an ironing table.

5 In ironing or pressing garments it will be understood that substantial pressures are exerted upon the upper surface of the ironing-board not only by the weight of the flat-iron but also by the additional pressure exerted upon the iron by 10 the operator as in pressing heavy fabrics, etc. In the construction of an ironing table great care must be taken to provide supporting elements arranged and constructed so that no matter where upon the surface of the ironing-board such 15 pressures are exerted, the board will be firmly held at its original elevation, without giving, receding, settling, or tipping. It is therefore desirable not only to construct the supporting elements strong enough to resist such pressures, but 20 also to arrange them so that the pressures will be properly distributed among the various supporting elements to prevent excessive forces from centering in one or more of said elements.

The principal object of my invention is to provide 25 a collapsible ironing table, the supporting elements of which not only provide a firm and rigid support for the ironing-board and properly distribute the pressure among said elements, but also provide an arrangement of said elements so that by one simple hand movement the elements 30 may be automatically extended to supporting position and conversely by an equally simple reverse movement said elements may be completely collapsed against the under surface of the board, 35 all without danger of pinching the operator's fingers during erection or collapse and without necessity of adjusting or positioning any element.

A further object is to provide a construction and arrangement of the supporting elements 40 whereby they are all interconnected either to each other or to the ironing-board, leaving no free or loose element which requires adjustment or positioning in erecting or collapsing the ironing-board.

45 A further object is to provide a strong, easily collapsible ironing table which may be economically manufactured and assembled.

A further object is to provide releasable locking means for the supporting elements of such 50 an ironing table in erected position to lock them in erected position and prevent accidental collapsing thereof.

Other objects relate to the construction and mode of operation and will be apparent from a 55 consideration of the following description and

accompanying drawings which exemplify one embodiment of my invention chosen for the purposes of illustration.

In the drawings:

Fig. 1 is a plan view of an embodiment of my ironing table showing the supporting elements in collapsed position; 5

Fig. 2 is a side elevation showing the supporting elements in partially erected position;

Fig. 3 is a side elevation showing the ironing 10 table in completely erected position; and

Fig. 4 is a fragmentary section looking in the direction of the arrows 4—4 in Fig. 3.

In the embodiment chosen for the purpose of illustration herein the top of the ironing 15 table comprises an ironing-board 10. Rear legs constituting a rear supporting member 11 are pivotally connected to the ironing board adjacent one end thereof as by the pivots 13 on either end of the longitudinal cleat 12, which is 20 firmly secured to the ironing board by screws or other means. An oblique leg 14 is provided having one end pivotally connected either to the rear supporting member or to the ironing board adjacent the end thereof to which said rear supporting member is connected, as by the pivots 13. The oblique leg 14 is preferably formed of two longitudinal elements, the free ends of which converge and are secured together by suitable means, as for example the headed bar 15. The 25 faces 16 of the cleat 12 are preferably cut at an angle corresponding to the angle taken by the respective longitudinal elements of the oblique leg, thus forming supporting surfaces against which said elements may rotate. 30

A compression member 17 is provided between the ironing board and the lower end of the oblique leg 14. The upper end of said compression member 17 is pivotally connected to the ironing board, preferably by means of headed rivets which pass through the downturned ends of a metallic strap 18 which is secured to the ironing board by means of screws, rivets or other suitable means. The lower end of the compression member 17 is 35 pivotally connected to a link member 19, which is pivotally connected to the lower end of the oblique leg 14 as by the headed bar 15. The compression member 17 is preferably constructed of two longitudinal elements, and a crossbar 20 is preferably provided between said elements adjacent the 40 lower ends thereof, said crossbar serving as a pivot for the link member 19 and connecting member 21, and also serving as means for firmly engaging the upper surface of the oblique leg 14 when the ironing table is in erected position (as shown in 45 50 55

- Figs. 3 and 4). The link member 19 is preferably constructed of two pieces, each having one end pivoted to the bar 15 and the other end pivoted to the bar 20.
- 5 A connecting member 21 is provided having one end pivotally connected to the rear supporting member, as by means of rivets and washers 22, and the other end pivotally connected to the compression member 17 or to the link member 19.
- 10 This connecting member is preferably constructed of two longitudinal elements.

In erected position the lower end of the compression member 17 firmly engages the oblique leg 14 by means of the crossbar 20 and the link member 19, and consequently the compressive forces in the compression member are transmitted directly to the lower end of the oblique leg and thence directly to the floor.

The connecting member 21 serves as a tension member between the compression member and/or the oblique leg on one end and the rear legs on the other end, and also serves to limit the outward movement of the rear legs and to collapse the rear legs.

25 The link member 19 guides the compression member 17, the crossbar 20 and the connecting member 21 from collapsed position to erected position and conversely. It also, in conjunction with the compression member, limits the outward movement of the oblique leg and it serves further, when the table is in erected position, to hold the crossbar 20 securely in engagement with the upper surface of the oblique leg by preventing the crossbar from sliding downwardly along said surface.

In my preferred embodiment I provide releasable locking means, such as the hook 23, pivotally connected to the oblique leg and adapted to detachably engage means connected with the link member, for example the crossbar 20, when the legs are in erected position, to lock said link member against pivotal movement, thus locking the legs in erected position. It will be understood that since in erected position (see Fig. 3) the link member 19 has been swung past its dead center the compressive forces exerted by the compression member 17 and the crossbar 20 will prevent the link member 19 from swinging in a clockwise direction (looking at Fig. 3) and consequently will prevent the ironing table from accidentally collapsing. However, if the ironing table is tipped up on its wide end the compressive force exerted by gravity or otherwise will tend to be discontinued in the compression member 17 and the force of gravity will swing the oblique leg in a clockwise direction, thus also tending to swing the link member 19 in a clockwise direction past its dead center, and consequently the table in such a position may be completely collapsed by the force of gravity. It will be understood, however, that so long as the ironing-board is in a horizontal position there is no such tendency to collapse by gravity. The releasable locking means 23 is therefore provided to prevent such collapsing by gravity when the table is tipped on end, but it will be understood that such collapsing may also be prevented by the operator grasping either the connecting member 21 or the compression member 17 when tipping the table on end, and easing or controlling the pivotal movement of the link member past its dead center and to fully collapsed position.

In my preferred embodiment I provide a knob or handle 24, near the end of the connecting member

21, for the operator to grasp with one hand in erecting or collapsing the ironing table.

A collapsible ironing table constructed in the manner described above, provides a durable, strong and economical table readily and simply set up or collapsed, with all of its elements interconnected, eliminating free ends to be positioned or adjusted, and with its supporting elements arranged to provide a rigid support and also to be set up or collapsed automatically by one simple hand movement.

To erect the ironing table I recommend placing the ironing table in a vertical position with its wide end resting upon the floor, with one hand grasping the narrow end of the ironing board 15 and the other hand grasping the connecting member, as by the knob 24. Then by a simple counterclockwise movement (looking at Fig. 2) of the connecting member or knob 24 and the link member, the link member is easily revolved past its dead center and the legs are automatically moved into extended position, the compression member 17, the crossbar 20, and the connecting member 21 simultaneously being moved to extended position, as indicated in Fig. 3. The table 25 is then ready for use by merely placing the ironing board in horizontal position. In collapsing the ironing table the connecting member, the knob 24 and the link member 19 are revolved in clockwise direction (looking at Fig. 2).

If desired the releasable locking means 23 may be revolved into engagement with the link member 19 or the crossbar 20 after the supporting elements have been revolved into extended position but, as explained above, the ironing table is 35 satisfactory without such releasable locking means.

The present disclosure is for the purpose of illustration only and this invention includes all modifications and equivalents which fall within 40 the scope of the appended claims.

I claim:

1. A collapsible ironing table comprising an ironing board member, rear legs constituting a rear supporting member pivoted to said board, 45 an oblique leg pivoted to at least one of said members, a compression member having its upper end pivotally connected to said board, means on the lower end of said compression member to engage said oblique leg when the table is in 50 erected position, a connecting member having one end pivotally connected to said compression member and the other end pivotally connected to the rear supporting member, and a link member pivotally connecting the oblique leg and said 55 compression member.

2. A collapsible ironing table comprising an ironing board member, rear legs constituting a rear supporting member pivoted to said board, 60 an oblique leg pivoted to at least one of said members, a compression member having its upper end pivotally connected to said board, means on the lower end of said compression member to engage said oblique leg when the table is in 65 erected position, a connecting member having one end pivotally connected to said compression member and the other end pivotally connected to the rear supporting member, and a link member pivotally connecting the oblique leg and said connecting member.

3. A collapsible ironing table comprising an ironing board member, rear legs constituting a rear supporting member pivoted to said board, 70 an oblique leg pivoted to at least one of said members, a compression member having its up- 75

- per end pivotally connected to said board, means on the lower end of said compression member to engage said oblique leg when the table is in erected position, a connecting member having 5 one end pivotally connected to said compression member and the other end pivotally connected to the rear supporting member, and a link member having one end pivotally connected to the oblique leg and the other end pivotally connected 10 to said compression member and said connecting member.
4. A collapsible ironing table comprising an ironing board member, rear legs constituting a rear supporting member pivoted to said board, an 15 oblique leg pivoted to at least one of said members, a compression member having its upper end pivotally connected to said board medially thereof, means on the lower end of said compression member to engage said oblique leg when the table is in erected position, a connecting member having one end pivotally connected to said compression member and the other end pivotally connected to the rear supporting member, and a link member pivotally connecting the oblique 20 leg and said compression member.
5. A collapsible ironing table comprising an ironing board member, rear legs constituting a rear supporting member pivoted to said board, an oblique leg pivoted to at least one of said members, a compression member having its upper 25 end pivotally connected to said board, means on the lower end of said compression member to engage said oblique leg when the table is in erected position, a connecting member having one end pivotally connected to said compression member and the other end pivotally connected to the rear supporting member, a link member pivotally connecting the oblique leg and the compression member, and releasable locking means to lock said link member against pivotal movement when the table is in erected position. 30
